ATTORNEY

UNITED STATES PATENT OFFICE.

HEINRICH BÖHLE, OF SPANDAU, PRUSSIA, GERMAN EMPIRE.

FIRE-EXTINGUISHER.

SPECIFICATION forming part of Letters Patent No. 223,984, dated February 3, 1880.

Application filed December 17, 1879.

To all whom it may concern:

Be it known that I, HEINRICH BÖHLE, of the city of Spandau, in the Kingdom of Prussia, German Empire, have invented Improvements in Fire-Extinguishers, of which the following is a specification.

In the accompanying drawings, Figure 1 represents a vertical central section of the acid-bottle and its connection with the body 10 of the extinguisher, on an enlarged scale; Fig. 2, a vertical central section of the extinguisher; and Fig. 3, a vertical central section of my improved connection between the body and bottom of the apparatus.

Similar letters of reference indicate corresponding parts.

This invention relates to improvements in fire-extinguishers of that class in which, by the breaking of an acid-bottle, the acid is allowed 20 to escape and to evolve the carbonic-acid gas by reaction with the ingredients dissolved in the water.

The invention consists of an acid-bottle the 25 walls of which are made thinner toward the bottom and provided with an annular contraction near the bottom, so as to be readily broken by pressure on the top of the bottle.

The acid-bottle is placed in a metallic casing or jacket, having at the lower part perforations for the gradual escape of the acid, it being provided at the bottom part by a wire-gauze lining, to retain small pieces of broken glass.

The invention consists, further, of a device 35 for tightening the packing of the stuffing-box of the pressure-screw after the bottle has been broken; and, finally, of a detachable bottom or top, which is screwed into the body of the apparatus and provided with a recessed flange 40 or rim for facilitating the removal of the bottom or top for cleaning the apparatus.

Referring to the drawings, A represents the body of my improved fire-extinguishing apparatus, at the upper part of which the acid-bottle B is held suspended by a cylindrical casing or jacket, C, of suitable sheet metal. The acid-bottle B is made of glass or other suitable material, the wall of which is of considerable thickness at the neck, and then made 45 gradually thinner toward the bottom, being 50 thinnest at the bottom part. The acid-bottle

is closed by means of a plug, which is ground into the neck and secured hermetically thereto by a paraffine seal. The bottle is preferably arranged near the bottom with an annular contraction, b, or with any other equivalent depression, by which the bottle is weakened at that point to such a degree that it may be readily broken at that point as soon as a proper pressure is exerted on the top of 55 the bottle.

The inclosing-jacket C is screwed into the closing top screw, C', of the apparatus. At the lower part the jacket is provided with perforations d, and lined at the inside with a 65 wire-gauze covering, C², which forms a kind of spring-cushion for the acid-bottle, and serves also to prevent the escape of small pieces of broken glass to the interior of the body.

The pressure-screw D turns in an interior screw-thread of the top screw, C'. The stuffing-box e secures the tight connection between pressure-screw and top screw, while a hand-crank, D', at the upper end of the pressure-screw D, serves for turning the pressure-screw. 70 By turning the pressure-screw D downward the lower end of the same presses on the top of the acid-bottle and causes the breaking of the bottle by the crushing of the thinner bottom part of the same. The acid escapes then 75 gradually through the holes of the jacket, mingles with the water in the body of the apparatus, which water is charged with bicarbonate of soda, and produces, by the reaction of the chemicals, the generation of carbonic-acid gas, which takes place but slowly, owing 80 to the gradual escape of the acid.

To prevent the accidental breaking of the bottle or any tampering therewith, a collar, f, is interposed between the inclosing screw-nut of the stuffing-box and a shoulder, f', of the crank-handle D', said collar being made of two hinged semi-sections, which are held together by means of perforated ears, a connecting-wire and a lead seal, as shown in Fig. 90 1. The collar f is attached by a chain to the apparatus. When the collar is applied it serves to arrest the motion of the pressure-screw, and prevents the breaking of the acid-bottle. When it is removed it admits the 95 screwing down of the screw.

The shoulder f' of the crank-handle presses

finally on the flanged head f^2 of the stuffing-box, and secures the compressing and reliable fitting of the packing around the shank of the screw, even if the same should not be properly disposed around the same.

5 To facilitate the cleaning of the apparatus, which could hitherto only be accomplished through the comparatively small top opening of the body, the bottom or top, or both, are secured to the body, not by riveting, but by attaching them to the body A, in the manner shown in Fig. 3, by screwing them tightly over the exteriorly-threaded portion of the body.

10 The bottom E has an outwardly-flaring flange, E', on which the extinguisher rests, the weight of the same securing the tight connection of the bottom and body.

15 The flange E' is recessed at diametrically opposite points, to insert a hand-lever for screwing on or unscrewing the bottom in a 20 convenient manner.

25 The apparatus may, by the detachable bottom, be cleaned in a convenient manner, and then the apparatus quickly thrown into action by turning the pressure-screw after releasing the sectional collar.

Having thus described my invention, I claim as new and desire to secure by Letters Patent—

30 1. In fire-extinguishers, an acid-bottle which is made thicker at the upper part and thinner at the lower part, and provided with an annular contraction near the bottom, substantially as set forth.

2. In fire-extinguishers, the combination of 35 an acid-bottle, made with thinner walls at the lower part, with an inclosing-jacket having perforations at the lower part, and with a pressure-screw for breaking the bottle by pressure on the top thereof, substantially as specified.

3. In fire-extinguishers, the combination of 40 an acid-bottle, made with thinner walls at the lower part, with an inclosing-jacket having perforations, and with an intermediate guard- 45 screen of wire-gauze, substantially as described.

4. In fire-extinguishers, the combination of 45 the stuffing-box of the pressure-screw with the crank-handle of the pressure-screw, having a shoulder which is adapted to compress the packing of the stuffing-box on lowering the pressure-screw, substantially as set forth.

5. In fire-extinguishers, the combination of 50 the body of the apparatus, having exterior screw-thread, with a threaded top or bottom, having a rim or flange with recesses at opposite points, for the purpose described.

In testimony whereof I have signed my name to this specification in the presence of two sub- 55 scribing witnesses.

HEINRICH BÖHLE.
